DESIGN FOR A BURIAL VAULT

Roe P. Henderson, Springfield, Ohio, assignor to
The Springfield Metallic Casket Company,
Springfield, Ohio, a corporation of Ohio

Application June 11, 1934, Serial No. 52,125

Term of patent 7 years

To all whom it may concern:

Be it known that I, ROE P. HENDERSON, a citizen of the United States, residing at Springfield, in the county of Clark and State of Ohio, have invented a new, original, and ornamental Design for a Burial Vault, of which the following is a specification, reference being had to the accompanying drawing, forming part thereof.

The figure is a view in perspective of a burial vault, showing my new design.

I claim:

The ornamental design for a burial vault, as shown.

ROE P. HENDERSON.
